Attorneys

UNITED STATES PATENT OFFICE.

LUCY COTTON AMENT, OF NEW YORK, N. Y.

MIRROR ATTACHMENT FOR TOILET ARTICLES.

Application filed July 21, 1927. Serial No. 207,512.

My invention relates to an attachment for toilet articles generally but specifically to a detachable mirror cap for lip-sticks or lip-stick holders.

The principal object of my invention is to provide as an article of manufacture, a spring clip carrying a mirror, for attachment to the cover of lip-stick cases already manufactured and in use and for sale and attachment to cases so as to be marketed as a composite whole. Such a device is of extreme utility in that the cap may be removed with one hand thus exposing the lip-stick proper and the mirror thereon used while the lip-stick is being applied.

The invention contemplates a spring clip carrying a small convex bevelled mirror so as to catch a maximum vista. The clip itself is provided with a series of spring prongs so as to accommodate itself to lip-stick caps or cases of various sizes, yet to more or less rigidly grip said cap so that the clip and mirror will not be readily or accidentally displaced.

The invention further consists in the novel arrangement, combination and construction of parts more fully hereinafter described and shown in the drawings.

In the drawings:—

Fig. 1 is a perspective view of one embodiment of my device in use.

Fig. 2 is a sectional elevation.

Fig. 3 is a plan view.

In the particular embodiment illustrated, I have indicated a lip-stick receptacle or case at 1 having a lip-stick 2 held therein in the usual manner. The ordinary case cap is shown at 3 which telescopically engages the case body 1 to cover and protect the stick proper.

As an example, my invention may be embodied in a spring cap or clip comprising a cylindrical body portion 4 into one end of which is spun, crimped or suitably secured a small convex bevelled mirror 5. The de-

pending skirt of the cap is provided with a series of spring arms 6 flared outwardly at their ends as at 7.

Obviously, the inside diameter of the cap body is such as to accommodate any of a maximum number of different sized lip-stick caps now on the market. Any difference in size or looseness of fit may be readily taken up by deforming the spring arms, in or out as the circumstances require.

It will be clear that such an attachment has its chief value in that it is a readily detachable device and may be transferred from one case to another as the contents become exhausted. The body of the device may be of any desired material, either to match in quality the lip-stick case to which it is to be attached or to appeal to the aesthetic taste by contrast thereto.

The device may be sold separately as an individual article of manufacture or attached to a lip-stick case as a composite article.

The mirror 5 may be protected by backing 8 and a protective disc 9.

What I claim is:

1. In combination, a lip-stick case comprising a body and a cover, a cylindrical spring member carrying a mirror, spring clipped to said cover.

2. In combination, a lip-stick case comprising a body and a cover, a cylindrical member overlying the cover, the skirt of the cylindrical member being provided with a series of spring arms in engagement with the cover, and a convex bevelled mirror carried at the top of the cylindrical member.

3. As an article of manufacture, a cap for toilet articles comprising a cylindrical body having spring arms depending therefrom, and a mirror carried in the top of the cylindrical body.

In testimony whereof, I affix my signature.

LUCY COTTON AMENT.
